UNITED STATES PATENT OFFICE.

MORTIMER A. CLAPP, OF AUBURN, NEW YORK, ASSIGNOR TO D. M. OSBORNE & COMPANY, OF SAME PLACE.

HARVESTER-REEL.

SPECIFICATION forming part of Letters Patent No. 377,372, dated February 7, 1888.

Application filed December 4, 1886. Serial No. 220,671. (No model.)

To all whom it may concern:

Be it known that I, MORTIMER A. CLAPP, of Auburn, in the county of Cayuga and State of New York, have invented certain Improvements in Reels for Harvesters, of which the following is a specification.

My invention has reference to that class of reel mechanisms in which a horizontal rock-shaft is provided with a crank-arm carrying the bearings of the horizontal reel-shaft, so that the turning motion of the rock-shaft will have the effect of raising and lowering the reel.

The particular aim of the invention is to simplify the mechanism for operating the rock-shaft, to give the operator convenient control of the reel in its various operative positions, and to admit of the reel being thrown inward or rearward from its operative position to reduce the space occupied by the machine and to facilitate its storage or transportation.

Referring to the accompanying drawings, Figure 1 represents a side elevation of the reel-supporting mechanism constructed on my plan. Fig. 2 is a front elevation of the same. Figs. 3, 4, and 5 are diagrams illustrating the principal positions of the parts.

In the drawings, A A represent two bearings fixed to standards or other suitable supports, and containing the horizontal rock-shaft B, the overhanging end of which is fashioned into or provided with a crank-arm carrying at its outer end bearings C of any suitable character, in which the horizontal reel-shaft D is mounted, the reel being of the usual overhung type. The crank-arm is extended a sufficient distance to receive one or more reel-shaft bearings, C, which will be secured rigidly thereon by set-screws or their equivalents. These details may be of any ordinary construction, as they constitute no part of my invention, and are now known in the art in various forms. It will be perceived that the shaft B thus arranged serves to support the reel-shaft, and that when revolved in its bearings A the crank-arm, sweeping through the vertical path, will have the effect of raising and lowering the reel-shaft. To the rock-shaft B, I fix firmly a laterally-projecting arm, E. To a bracket-plate, F, or other rigid support, I pivot a hand-lever, G, connecting the same at a suitable point in

its length by a link, H, to the arm E of the rock-shaft.

I provide the hand-lever with a sliding catch or dog, I, controlled by a thumb-lever, J, and arranged to engage in stationary locking-teeth K, which may be formed on the rear edge of the bracket F, as shown, or otherwise. The locking-dog, as shown, is of a form familiar to those skilled in the art, and it may be replaced by any other equivalent locking device which will serve to hold the hand-lever in its different positions. When the reel is in operative position, its shaft stands in front of a vertical line passing through the shaft B.

In Figs. 1 and 3 the reel is shown in its lowest operative position, its shaft standing almost directly under the rock-shaft B and the hand-lever standing in its highest position. On depressing the lever the link H, acting through the arm E, will turn the rock-shaft B, and thus carry the crank-arm and reel-shaft upward until they assume their highest operative positions. (Represented in Fig. 4.) By locking the hand-lever at suitable points the reel may be sustained at any desired elevation between the extremes represented in Figs. 3 and 4.

When it is desired to throw the reel rearward beyond its ordinary position, it is first lowered in a forward direction by elevating the lever and then thrown sharply upward by a sudden depression of the lever, care being taken to give it such momentum that the crank-arm will be carried upward and rearward past the center, or, in other words, past the vertical line falling through the shaft D, whereupon the elevation of the lever, owing to the changed relation of the parts, will permit the reel to descend to the position indicated by full lines in Fig. 5. It will be observed that when thus adjusted the reel stands in rear of its ordinary operative position. It may be carried forward and returned to its operative position by sharply depressing the lever, so as to throw the crank forward over the center.

It will be perceived that the reel-sustaining crank and the controlling-arm E project from the shaft in directions which are almost diametrically opposite, and that the various parts are so arranged that the crank B may make nearly an entire revolution. These facts are

of importance, in that they permit the crank to be swung through a very long arc by the lever, and that they permit the parts to assume such relative positions that the reel may be given sufficient momentum to throw it over the center with certainty.

I am aware that a vibratory frame supporting the reel has been provided with an arm extending at right angles thereto and connected by a link to a hand-lever, the organization being such that the lever would serve to vibrate the frame through a short arc in a vertical direction; but I believe myself to be the first to so arrange the parts that the reel can be practically thrown rearward beyond the axis of its sustaining-crank and beyond its operative position at will.

The essence of my invention resides in providing the rocking crank-shaft which carries the reel with a hand-lever with devices which admit of the crank being thrown forward and backward of its axis, and it is manifest that the details of construction may be modified at will within the range of mechanical skill without departing from my invention.

Having thus described my invention, what I claim is—

1. In a harvester, the horizontal rock-shaft mounted in fixed bearings and having the overhung cranked end, in combination with the reel-shaft carried by said cranked end, an arm, E, secured rigidly to the rock-shaft and extending therefrom in an opposite direction

from the crank, a hand-lever, G, pivoted to the frame below the rock-shaft, a link, H, extending from the hand-lever to the arm E, and a locking device for holding the lever in different positions, said elements combined and arranged, as described, to admit of the reel being adjusted vertically to different operative 40 positions forward of the rock-shaft, or of its being thrown downward and rearward in relation to the rock-shaft, as described.

2. In a harvester, the horizontal rock-shaft B, having the cranked end, the stationary 45 bearings for said shaft, the horizontal reel-shaft carried by the crank-arm of the rock-shaft, the arm E, fixed to the rock-shaft and extended in opposition to the crank, the stationary toothed plate F, the hand-lever G, 50 pivoted to said plate below the rock-shaft, a link, H, connecting said lever with the arm E, as described and shown, and the locking-dog I, to hold the lever in different positions, said parts constructed and arranged as described, 55 whereby the reel may be adjusted and fixed at different heights in advance of the rock-shaft for action or folded downward in rear of the rock-shaft for transportation.

In testimony whereof I hereunto set my hand, this 9th day of November, 1886, in the presence of two attesting witnesses.

MORTIMER A. CLAPP.
